UNITED STATES PATENT OFFICE

2,539,810

DEVICE FOR IDENTIFYING A PARTICULAR
ENTRY IN A HORSE RACEJames S. Butler, Lewiston, Maine, assignor to
Butler Head Number, Inc., Lewiston, Maine, a
corporation of Maine

Application October 9, 1947, Serial No. 778,856

2 Claims. (Cl. 40—10)

1

In my Patent Number 2,114,135, granted April 12, 1938 the principal object of the invention is to employ a device for identifying a particular entry in a horse race and consists of a disc, supported on the head of the horse, between its ears, with a numeral or other identifying indicia, on each side of the disc, clearly visible to the spectators. The disc, in accordance with the teaching of said patent, is held in position by arms which engage portions of the bridle on opposite sides of the horse's head. The device of said patent has been found to be satisfactory but experiments have proven that some of the parts may be eliminated without curtailing or reducing the advantages. An important object of the present invention is to provide an identifying device of this character which uses the same desirable indicia bearing disc vertically positioned between the horse's ears with, however, a complete absence of head embracing parts, and embodying a simple bridle embracing means which may be snapped into engagement with the bridle and released from the latter expeditiously yet positively holding the identifying disc from casual displacement or interference with the jockey.

It is also within the contemplation of this invention to provide an indicia bearing disc and securing clip therefor which are directly secured together, the clip when in use being held from contact with the horse by a resilient pad.

Other objects of the invention will be apparent from the following description of the present preferred form of the invention taken in connection with the accompanying drawings, wherein—

Figure 1 is a perspective view of an identifying means, constructed in accordance with the present invention illustrating its application;

Figure 2 is a side elevational view of the identifying device per se showing to advantage the manner of connecting the base of the identifying disc to the clasp;

Figure 3 is an edge elevational view of the same; and

Figure 4 is a perspective view of the device showing it in use on a bridle strap.

The device of the present invention consists of a plate or disc 5, preferably made of metal, and provided on the opposite faces thereof with identifying indicia 6. The plate or disc 5 issues into an extension 7, the lower or base terminal of which is bent at right angles, as indicated at 8. The right angle portion 8 serves as an anchorage for a clasp or clip 9, the axis of the latter

being substantially midway the ends of the part 8. The top of the clasp 9 is riveted or otherwise fixedly secured to the right angle portion 8, as indicated at 10. The clasp includes handles 11 at one end and jaws 12 at the opposite end, the jaws being adapted for engagement with a bridle 13 as indicated in Figure 4.

For the purpose of preventing contact of the bottom of the clasp 9 with the horse, a resilient pad 14 is provided which is preferably made of soft rubber and covers the bottom face of the clasp from a point in proximity to its handle 11 to a point adjacent the extremity of its jaws 12.

In use of this device the handles 11 are relatively moved to separate the jaws 12 permitting the bridle strap 13 to be engaged there between. The strap 13 is preferably engaged between the jaws 12 as illustrated in Figure 4. In this position, one margin of the strap bears against hinge 15 of the jaws, the latter serving as an abutment to limit inward movement of the strap. The outer margin of the strap, as shown in Figure 4, projects beyond the free ends of the jaws 12. The jaws 12, as shown in Figures 3 and 4, are elongated so as to obtain a substantial purchase on the strap with obvious beneficial results. Consequently, in engaging the clasp with the bridle, when the handles 11 are compressed and the jaws open, the jaws may be engaged with the strap by a sliding movement of the entire identifying device until the bridle strap comes into contact with the hinge 15. This eliminates the possibility of play when the identifying device is engaged with the bridle and, correspondingly, eliminates the possibility of annoyance to the horse or the jockey.

It is understood that various changes may be made in this device within the scope of the claims herein appended.

What I claim is:

1. A device for identifying a particular entry in a horse race comprising, in combination with a bridle one of the straps of which extends across the head of the horse just aft of the ears, an indicia bearing plate equipped with an extension the free end of which is at right angles to the plate, a clasp secured to the right angle portion of the plate extension and including yieldable jaws which extend at right angles to the plate, said plate being secured to one of the jaws, the jaws adapted to be snapped into engagement with said bridle strap to support the plate in an upright position on the horse, approximately between the ears.

2. A device as set out in claim 1 wherein the

length of the jaws between the hinge and free terminals of the jaws is less than the width of the strap whereby one margin of the strap bears against the hinge of the jaws to limit inward movement of the strap between the jaws.

JAMES S. BUTLER.
